[57] CLAIM

The ornamental design for a combined cleaning component holders and tray therefor, substantially as shown and described.

DESCRIPTION

FIG. 1 is a top plan view of the combined cleaning component holders and tray therefor showing my new design;

FIG. 2 is a front elevational view thereof;

FIG. 3 is a side elevational view, taken from the right of FIG. 2, the other side being a mirror image thereof;

FIG. 4 is a view taken along the line 4—4 of FIG. 1;

FIG. 5 is a rear elevational view thereof;

FIG. 6 is a bottom plan view thereof; and

FIG. 7 is a perspective view of the tray with the holders removed for convenience of illustration.

FIG. 5

FIG. 6
